PROCESS FOR TREATING PETROLEUM
HYDROCARBONS

Albert G. Davis, Elizabeth, N. J., assignor, by
mesne assignments, to Gasoline Products
Company, Inc., Wilmington, Del., a Corpora-
tion of Delaware

Application December 10, 1925
Serial No. 74,507

4 Claims. (Cl. 196—97)

This invention relates to improvements in processes for treating petroleum hydrocarbons, and refers more particularly to processes for the production of products having the characteristics of gasoline and the like. The system consists primarily of a double stage process, the cracking or conversion of the oil taking place in one portion of the system, while the distillation of the cracked products is effected in separate stages directly connected to the cracking stages and separated therefrom by a pressure reduction means.

The novelty in the invention lies primarily in the return of the incondensable gases withdrawn from the final stage of separation, which gases are injected back into the fractionating stage to promote redistillation of the condensate and absorption of the lighter fractions of the oil from the refluxed material.

20 The single figure is a diagrammatic side elevational view of the apparatus with parts in section and parts broken away.

Referring to the drawing, at 1 is shown a furnace in which are mounted the heating coils 2 connected by means of a transfer line 3 to a heavily insulated forged steel reaction chamber 4. The reaction chamber, in turn, is connected by a transfer line 5 in which is interposed a pressure reduction valve 6 to an evaporator 7.

25 At 8 is shown a fractionating tower in the form of a bubble tower connected by a vapor line 9 to the top of the evaporator and having a vapor line 10 leading off from the top thereof to a condenser coil 11 positioned in the condenser box 12. The discharge line from the condenser coil terminates in a pipe 13, directing the oil to a gas separator 14. The gas separator is equipped with a liquid draw off line 15 regulated by a valve 16 and a gas line 17 controlled by a valve 18.

30 The gas line 17 is divided by T connection forming the line 18^a controlled by a valve 19 which directs the gas from the system and a line 20 regulated by a valve 21 which is connected to the suction side of the pump 22 by means of which the gas is discharged through the line 23 either directly back into the bottom of the bubble tower or it is circulated through a heater 24 by closing the valve 25 whereby the gas is heated to the desired temperature before its introduction 45 or injection into the fractionating tower. The evaporator 7 is equipped with a liquid level draw off line 26 controlled by a valve 27 through an automatic liquid level regulating device 28. The liquid withdrawn is passed through a cooling coil 29 and thence to storage through the

line 30. In a like manner, the liquid withdrawn from the fractionating tower through the line 31 is directed through the cooling coil 32 and thence through the line 33 to a recharging stock tank or to storage. Instead of cooling the condensate withdrawn from the fractionating tower, it may be recharged directly to the heating coils for retreatment in the system. These connections have been eliminated for simplicity but are easily made with the charging line.

In operation, the cracking stock is introduced from any convenient source through the line 34 and is charged by means of the pump 35 into the top of the fractionating tower, being circulated therethrough in a closed coil 36. The preheated oil passes thence through the line 37 into the heating coils where it is raised to a cracking temperature. The velocity of the oil through the heating coils is so regulated that the oil receives sufficient heat therein to produce the desired amount of conversion in the subsequent reaction stage but is not overheated to the extent that there is any substantial deposition of carbon in the coils. The highly heated oil is directed thence through the transfer line 3 to the reaction chamber where the major portion of the reaction takes place.

Temperatures of from 550° to 1,000° F. are maintained in the heating and reaction stages, while pressures are imposed sufficient to prevent any substantial vaporization ranging from 450 to 1500 pounds per square inch. The converted products are directed from the reaction stage into the evaporating tower through the line 5, pressure being reduced to substantially atmospheric conditions at the valve 6.

In the evaporating stage the lighter fractions will distill off, the unvaporized portions being automatically withdrawn by the liquid level regulating device. These drawn off liquids consist primarily of the heavier oils, such as fuel oil, which are cooled and directed to storage through the line 30. The overhead material passes off in vapor form through the line 9 and is introduced into the bottom of the fractionating tower or bubble tower where it is subjected to a refluxing or dephlegmating action by being caused to rise through a plurality of pools of progressively cooler oil. After dephlegmation or fractionation in the tower, the vapors pass overhead through the line 10 and are subjected to a final condensing action, being cooled as liquid distillate in the gas separator 14. The bottoms accumulating in the fractionating tower are automatically discharged either into the cooler and

to a recharging stock storage tank, or, without cooling, directly back into the heating coil.

The incondensible gas taken off from the gas separator through the line 17 may be removed from the system or portions thereof may be removed while the remaining gas is recirculated through the pipe 20 and pump 22 through the line 23 into the bottom of the fractionating tower where it is injected into the pool of oil accumulated therein. Under certain conditions it may prove to be advantageous to preheat the gas prior to its injection into the fractionating tower. For this purpose, there is interposed in the line 23, a heating coil 23^a positioned in a heater 24. This heater serves to raise the temperature of the recycled gases promoting redistillation of the lighter fractions from the condensate on injection of the heated gases back into the tower.

20 It is a well known practice to inject incondensible gases, steam, hydrogen, oxygen or inert gas such as carbonic acid gas, into the vaporizing or reaction stage of the cracking system and heretofore steam has been injected into the fractionating stage of both a cracking system and atmospheric distillation system to promote redistillation of the low boiling point fractions. It is thought novel, however, to return the incondensible gases to the fractionating stage and 25 there inject them into the fractionating tower where they are combined with the vapors rising through the tower. Furthermore, this practice has given considerable satisfaction both where the gases are heated and where they are unheated, as they absorb from the condensate considerable quantities of the lighter fractions which are separated out during the fractionating of the vapors.

30 I claim as my invention:

40 1. A process of converting petroleum hydrocarbons, comprising the steps of subjecting the oil to cracking temperatures and pressures, distilling off the lighter products, removing and fractionating the vapors, subjecting the still un-

condensed vapors to a final condensing action and separating the distillate from the uncondensable gas, returning said gas directly to the fractionating stage and percolating it through a pool of the condensate collected in the bottom of the fractionating stage.

80

2. A process for converting petroleum hydrocarbons, comprising the steps of subjecting the oil to cracking temperatures and pressures, reducing the pressure on the oil and distilling off the lighter products and subjecting the evaporated products to fractionation, passing uncondensed vapors to a condensing stage, separating the distillate from the uncondensable gases, passing the gas to a heating stage and thereafter returning it directly to the fractionating stage.

85

3. A process of converting petroleum hydrocarbons comprising the steps of subjecting oil to cracking temperatures and pressures, reducing the pressure on the treated oil and distilling off the lighter products, fractionating the evolved vapors in a fractionating stage, condensing the condensable components of said vapors and returning the incondensable components into a pool of condensate in the fractionating stage.

90

4. A process for cracking hydrocarbon oil comprising maintaining the hydrocarbon constituents under cracking conditions of temperature and pressure in a still, removing vaporous constituents from the still, subjecting the vaporous constituents to dephlegmation in a zone apart from the still, subjecting the dephlegmated vapors to condensation, collecting the resulting condensate and uncondensable gases, raising the temperature of portions of the uncondensable gases produced in the process to above the temperature of the vapors entering the dephlegmating zone and returning the same directly to the dephlegmating zone to facilitate the release of gasoline-like fractions from the condensate separated from the vapors in the dephlegmating zone.
